REED SWITCH ENVELOPE

Bernard Edward Shlesinger, Jr., 9411 MacKlin Court,
Alexandria, Va. 22309

Filed Dec. 29, 1970, Ser. No. 26,686

Term of patent 14 years

Int. Cl. D13—03

U.S. Cl. D26—13

FIG. 13

FIG. 11

FIG. 14

FIG. 12

FIG. 15

FIG. 16

FIG. 17

FIG. 18

FIG. 19

FIG. 21

FIG. 20

FIG. 22

FIG. 23

FIG. 24

FIG. 25

FIG. 26

FIG. 27

FIG. 28

FIG. 29

FIG. 31

FIG. 30

FIG. 1 is a top plan view of a reed switch envelope;
 FIG. 2 is a bottom plan view thereof;
 FIG. 3 is a front elevational view thereof;
 FIG. 4 is a left side elevational view thereof;
 FIG. 5 is a right side elevational view thereof;
 FIG. 6 is a rear elevational view thereof;

FIG. 7 is a top plan view of a modified form of the reed switch envelope described in FIG. 1 showing my new design;

FIG. 8 is a bottom plan view thereof;

FIG. 9 is a front elevational view thereof;

FIG. 10 is a right side elevational view thereof;

FIG. 11 is a top plan view of a modified form of the reed switch envelope described in FIG. 1 showing my new design;

FIG. 12 is a bottom plan view thereof;

FIG. 13 is a front elevational view thereof;

FIG. 14 is a right side elevational view thereof;

FIG. 15 is a left side elevational view thereof;

FIG. 16 is a rear elevational view thereof;

FIG. 17 is a top plan view of a modified form of the reed switch envelope described in FIG. 1 showing my new design;

FIG. 18 is a bottom plan view thereof;

FIG. 19 is a front elevational view thereof;

FIG. 20 is a rear elevational view thereof;

FIG. 21 is a right side elevational view thereof;

FIG. 22 is a top plan view of the modified form of the reed switch envelope described in FIG. 1 showing my new design;

FIG. 23 is a bottom plan view thereof;
 FIG. 24 is a front elevational view thereof;
 FIG. 25 is a rear elevational view thereof;
 FIG. 26 is a right side elevational view thereof;
 FIG. 27 is a top plan view of a modified form of the reed switch envelope described in FIG. 1 showing my new design;

FIG. 28 is a bottom plan view thereof;

FIG. 29 is a front elevational view thereof;

FIG. 30 is a right side elevational view thereof;

FIG. 31 is a right side elevational view thereof.

The sides opposite to the sides shown in FIGS. 21, 26 and 31 are mirror images of these respective figures. The side opposite to the side showing in FIG. 10 is a mirror image of FIG. 9.

The end view opposite to the front end view shown in FIG. 9, is a mirror image of the right side elevational view shown in FIG. 10.

I claim:

The ornamental design for a reed switch envelope, as shown and described.
